SHEAR MECHANISM FOR HEADERS

John H. Friedman, Tiffin, Ohio, assignor to The National Machinery Company, Tiffin, Ohio, a corporation of Ohio

Application March 31, 1945, Serial No. 586,001

15 Claims. (Cl. 10—72)

1

This invention relates to shearing mechanism for headers and the like.

The principal object of this invention is to minimize distortion and breaking of the ends of blanks sheared from elongated wire or rod stock. Another object is to greatly increase the range of lengths within which satisfactory blanks may be sheared off, including all of the usual range of blanks several diameters and more in length, down to blanks having a length of but one or less than one diameter. Another object is to prevent the dragging and hence distortion of the end of the sheared blank over the surface of the stock gauge in shearing. Other objects are to facilitate the gauging of the lengths of the blanks to be sheared, and the delivery of the sheared blanks into positions for subsequent upsetting, extruding, piercing or other working operations to form the desired article; to increase the life of the tools and dies for working the sheared blanks; and to increase the accuracy and uniformity of the blanks and articles.

Other and further objects, features and advantages will become apparent as the description proceeds.

The present application is a continuation of my co-pending application, Serial No. 453,985, filed August 7, 1942, which has been abandoned; Serial No. 547,849, filed August 3, 1944; and Serial No. 547,886, filed August 3, 1944, on which Patent No. 2,396,995 was granted March 19, 1946; the latter application, in turn, being a continuation in part of my application, Serial No. 423,900, filed December 22, 1941, which has been abandoned.

In the accompanying drawings:

Fig. 1 is a longitudinal sectional view through the stock feeding and die stations of a double-blown cold header arranged in accordance with my invention;

Fig. 2 is a longitudinal section through the die station showing a cut-off blank aligned with the die, and with the header slide advancing upon its first blow;

Fig. 3 is a view similar to Fig. 2, showing the parts as the header slide continues its movement on the first blow;

Fig. 4 is a view similar to Fig. 2 showing the arrangement of the parts and the blank at the completion of the first blow;

Fig. 5 is a view corresponding to Fig. 3 showing a die for use with relatively hard or non-ductile blanks;

Fig. 6 is a view corresponding to Fig. 4 showing the arrangement of the parts and the blank

2

at the completion of the first blow in a die such as shown in Fig. 5;

Fig. 7 is a fragmentary detailed horizontal section through the stock feeding station and cut-off arm of an arrangement for use with relatively long blanks or slugs; and

Fig. 8 is a horizontal section through the die and stock feeding stations of Fig. 7, and showing the punch at the end of the first stroke of the machine.

Like reference characters are utilized throughout the drawing to designate like parts.

For the sake of illustration, I have shown in Figs. 1 to 4 my shearing mechanism and tools applied to a conventional, double-blown, cold header of the solid die type. A suitable cold header of this type is illustrated in the patent to Clouse No. 1,932,396 and in my prior Patent No. 1,955,061. Generally speaking, I provide a machine embodying a bed frame carrying a die, a reciprocating header slide having a pair of punches, which are alternately moved into alignment with the die on successive strokes of the slide, means for shearing a blank from elongated stock and carrying it into alignment with the die prior to the working stroke of the first punch, and means for ejecting the blank from the die after the working stroke of the second punch.

In the accompanying drawings a portion of the bed frame of such a machine is indicated at 10. The frame is provided with a stock feeding tube 11 terminating in a shearing edge 12 at the die breast of the machine. A die 13 is carried by the bed frame 10 spaced from the stock feeding tube 11 and opens through the die breast of the machine. A knock out rod 14 is arranged to operate axially through the die 13 and, in retracted position, to form the bottom of the die, as illustrated in Fig. 1.

40 A shear arm 15 carrying a shearing bush 16 is arranged to be moved to align the bush 16 alternately with the stock feeding tube 11 and the die 13. The bush is shaped to closely fit the stock S fed through the tube 11 and is formed with a shearing edge 17 which cooperates with the shearing edge 12, when the shear arm 15 is moved toward the die 13, to shear off the length of the stock contained within the bush 16.

The frame of the machine also carries a stock gauge 18 arranged to limit the length of stock fed into the shearing bush 16. A plunger 19 is slidably mounted in the shearing bush 16 and is formed with a head 20 arranged to abut the stock gauge 18, as illustrated in Fig. 1. Thus 55 when the shearing bush 16 is aligned with the

stock feeding tube 11 and the stock S is fed forwardly, the advancing end of the stock moves the plunger 19 outwardly until its head 20 strikes the stock gauge 18, so that a definite length of stock is fed into and enclosed within the shearing bush 16.

The die 13 has a diameter larger than the diameter of the stock S. Preferably, the bottom of the die is formed with a conical or dome shaped shoulder 21 extending between the side wall of the die and the forward end of the knock out rod 14.

The first punch on the header slide 22 consists merely of an abutment member 23 arranged to engage the head 20 on the plunger 19. When the shear arm 15 moves from the position shown in Fig. 1 into its alternate position, with the bush 16 aligned with the die 13, the end of the stock confined within the bush 16 is sheared off and carried into alignment with the die, as illustrated in Fig. 2. The header slide 22 then advances and the punch 23 engages the head 20 of the plunger 19, thereby forcing the cut-off length of stock 24 axially out of the bush 16 and into the die 13.

Since the diameter of the stock is less than the diameter of the die 13, the stock is simply projected freely into the die space until its end engages the bottom of the die, at which time the opposite end of the stock is still confined within and guided by the bush 16, as illustrated in Fig. 3. The engagement of one end of the stock with the bottom of the die and the guiding of the opposite end of the bush 16 maintains the stock in axial alignment with the die and the advancing plunger 19. The conical or dome shaped shoulder 21 in the illustrated embodiment aids in centering the blank and maintaining its alignment as the upsetting action begins. Thus as the forward motion of the header slide 22 continues the cut-off piece 24 is upset smoothly, without buckling or cocking, into a slug 25 substantially fitting the opening of the die 13.

The length of the cut-off blank is selected so that when its end engages the conical or dome shaped shoulder 21 and the upsetting action begins as illustrated in Fig. 3, sufficient length of stock remains within the bush 16 to insure the correct starting of the upsetting action, while at the same time the length of the piece confined in the bush 16 is insufficient to cause the metal to bind in the bush or exert excessive pressure thereon. Preferably the end of the blank leaves the shearing bush 16 as soon as the upsetting has proceeded far enough to insure its proper completion without further guiding of the end of the blank, so that when the slug 25 is completed its forward face is spaced inwardly from the face of the die 13.

To insure the return of the plunger 19 from its position within the opening of the die 13 at the end of the first blow, as shown in Fig. 4, a spring 26 is coiled about the plunger 19 between the end of the bush 16 and the head 20. The extended length of the spring is preferably only sufficient to insure the return of the plunger 19 clear of the die to about the position illustrated in Fig. 3, and does not return the plunger a distance equal to the length of the blank, so that the head 20 of the plunger clears the gauge 18 when the shear arm returns to the position shown in Fig. 1. As the header slide 22 recedes after the completion of the first stroke the spring 26 forces the plunger 19 outwardly a sufficient distance to clear the die opening, after which

the shear arm 15 returns to the position illustrated in Fig. 1. When the shear bush 16 is again aligned with the feed tube 11, a new length of stock is fed forwardly until the plunger 19 is forced outwardly into engagement with the stock gauge 18.

At the completion of the first stroke the blank and the parts of the machine are prepared for a second plunger (not shown) in the header slide 22 to be moved into alignment with the die 13 for carrying out a further or final operation upon the blank for producing the finished article.

In some instances it may be desired merely to square up the sheared blank in the first operation, and an embodiment of the invention for this purpose is shown in Figs. 5 and 6. This arrangement is particularly useful in a multiple station transfer header, such as illustrated in the patent to Clouse No. 2,026,823, or the patent to Frayer No. 2,100,028.

For this purpose, as shown in Fig. 5, the die opening 31 is but slightly larger in diameter than the aperture in the shearing bush 16, which slidably receives the wire or rod stock from which the piece 32 is sheared. The sheared piece 32 is pushed completely out of the shear bush 16 into the die 31 before it contacts the die bottom 21, which as shown may be domed to impart a desired contour to the end of the blank. After the piece 32 has contacted the bottom of the die, the movement of the punch 23 continues so as to exert pressure on the piece through the plunger 19 and upset it into conformity with the die, forming the blank 33 shown in Fig. 6. By this operation, any irregularity or roughness of the sheared ends of the blank is corrected, and each blank is accurately sized to the diameter of the die 31.

In the embodiment shown in Figs. 5 and 6, as in that shown in Figs. 1-4, the spring 26 withdraws the plunger 19 from the die when the header slide carrying the punch 23 recedes and moves the plunger 19 away from the face of the die a distance less than the length of the blank being sheared, so that the plunger 19 clears both the die opening and the stock gauge 18 when the shear arm 15 moves to align the shearing bush with the incoming stock.

Figs. 7 and 8 illustrate an embodiment of the invention in which no spring is used to retract the plunger. The die and tools shown are particularly adapted for the making of hollow rivets, as disclosed in my application Serial No. 547,886, filed August 3, 1944.

As illustrated in Figs. 7 and 8, such a machine embodies a bed frame 41 carrying die and stock feeding stations on which there is mounted a reciprocating header slide, adapted to carry a pair of punches, each of which is aligned with the die in the bed frame on alternate strokes of the slide. Such a machine may be provided in accordance with my invention with a cut-off mechanism to cut off and carry over a new blank after every other stroke and similarly suitable ejection or knockout mechanism is provided to eject the finished article from the die after every two strokes of the header slide.

In accordance with this embodiment of the present invention, a die 42 is slidably positioned in a bore 43 in the bed frame 41. Behind and in alignment with the bore 43 the bed frame is provided in any suitable manner with a smaller bore 44 opening into an enlarged bore 45. A follower including a cup portion 46 slidably fitting in the bore 45 and a sleeve 47 slidably fitting

in the bore 44 is arranged to engage the rear end of the die 42. A spring 48 is positioned in the bore 45 bearing against the cup portion 46 and against a follower plate 49 which is also slidably fitted in the bore 45.

A knockout rod 50 is slidably supported in the frame coaxial with the die 42 and is provided intermediate its length with a flange 51 slidably bearing in a bore 52 behind and communicating with the bore 45. Ahead of the flange 51 the knockout rod includes a length 53 which passes through central apertures in the follower plate 49, the cup 46, and the sleeve 47, and enters a bore 54 in the die 42. A relatively small extension 55 is carried by the forward end of the knockout rod and slidably fits in the working bore 56 of the die. The extension 55 terminates in a piercing tool 57.

The forward sliding movement of the die 42 is adjustably limited in any suitable way, as by an adjustable stop 95 as shown in greater detail in my copending application, Serial No. 547,886, the stop 95 takes the form of a wedge slidably vertically, perpendicular to the plane of the section represented by Fig. 8. The wedge 95 is guided in a slot 96 in the bed frame and has a rearwardly facing wedge surface 97 cooperating with wedge surface 98 formed on the die.

With this arrangement the die 42 is normally held pushed forward in its bore 43 by the tension of the spring 48, with the wedge surfaces 97 and 98 in contact, while the die can be forced rearwardly a short distance by further compression of the spring 48. The spring 48 likewise acts as a return spring for the knock-out rod 50 when the same is advanced sufficiently to cause the flange 51 to engage the follower plate 49 and compress the spring from the rear end.

Rod or wire stock S is fed to the machine through a feeding aperture 75 in the bed frame arranged a short distance to one side of the die 42. The feeding aperture is provided at its forward face with a shear bush or die 76 with which cooperates a reciprocating cut-off arm 77. The cut-off arm 77 carries a shearing quill 78 having a central aperture 79 which, in the retracted position of the arm as illustrated in Fig. 7, is aligned with the opening in the bushing 76. A short plunger 80 is slidably mounted in the opening 79 of the shearing quill. A stock gauge 81 is also aligned with the feed opening in the bushing 76 and is arranged to abut the plunger 80 to limit the length of stock fed into the shearing quill 78, as shown in Fig. 7.

The face of the quill 78 adjacent the bushing 76 is formed with a cutting edge 82 arranged to lie closely adjacent the face of the bushing 76. On the opposite side the quill 78 is recessed or relieved as indicated at 83 to insure against interference with the end of the blank when the cut-off arm 77 is retracted.

The arm 77 is reciprocated or oscillated in any suitable manner so as to cut off a blank and carry the same into alignment with the aperture 56 in the die 42. After a length of stock has been fed into the quill 78 until the plunger 80 contracts the stock gauge 81, as shown in Fig. 7, the cut-off arm 77 is advanced to the position shown in Fig. 8. The shearing edge 82 severs the wire at the face of the bushing 76 and the quill 78 carries the blank so cut off and the plunger 80 into alignment with the opening 56 in the die 42. The cut-off arm is timed to dwell in alignment with the die during the first stroke of the header slide, at which time a punch 84 is advanced against the

plunger 80 as illustrated in Fig. 8. The punch 84 continues to advance and slides the plunger 80 through the quill 78 and pushes the cut-off blank into the opening 56 in the die 42 and against the end of the piercer 57.

The forward end of the piercer 57 is formed with a substantially conical point 85 for engagement with the end of the blank, and for the greater part of its length the piercer is relieved or reduced to a diameter less than the maximum diameter of the conical point 85, as indicated at 86. The length of the cut-off blank is so proportioned with respect to the position of the piercer 57 in the die and the movement of the punch 84 that at the end of the forward movement of the punch 84 the cut-off blank is pressed against the conical point 85 of the piercer and is upset slightly into full engagement with the wall of the opening 56 in the die. Preferably at the completion of this stroke the blank projects slightly from the face of the die as indicated in Fig. 8. The recess or relief 83 on the shearing quill 78 is of greater depth than the amount which the blank projects from the die at the completion of the first blow so that the cut-off arm 77 can be retracted without interference with the blank.

After the completion of the first heading stroke by the punch 84, the heading slide recedes and the cut-off arm is retracted into alignment with the shearing bush 76 ready to receive a new length of stock. The cut-off blank is then in position and the machine is ready to have any desired operation carried out on the cut-off blank such as a piercing operation, for example, if a hollow rivet is to be produced from the blank.

I have herein shown and particularly described certain embodiments of my invention and certain methods of operation embraced therein for the purpose of explaining its principle of operation and showing its application but it will be obvious to those skilled in the art that many modifications and variations are possible and I am, therefore, to cover all such modifications and variations as fall within the scope of my invention which is defined in the appended claims.

What is claimed is:

1. In a header having a die cavity, a shear bushing adjacent the die cavity, and a passageway for feeding elongated stock through the bushing; shearing mechanism comprising a movable member carrying a quill adapted to be moved alternately into alignment with said shear bushing and into alignment with said die cavity, said quill having a bore adapted to receive a length of stock fed through said bushing and a cutting edge arranged to sever said length of stock and carry the same into alignment with said die cavity, a pin slidably mounted in the bore of said quill, and a heading tool arranged to engage said pin to move said length of stock out of said quill and into said die cavity, said heading tool and pin ejecting said stock completely into said die cavity.

2. In a header having a die, a shear bushing adjacent the die, and a passageway for feeding elongated stock through the bushing; shearing mechanism comprising a movable arm carrying a quill adapted to be moved alternately into alignment with said bushing and into alignment with said die, said quill having a bore adapted to receive a length of stock fed through said bushing and a cutting edge arranged to sever said length of stock and carry the same into alignment with said die, a pin slidably mounted in the bore of said quill, and a heading tool arranged to engage said pin to move said length of stock out of said quill and into said die cavity, said heading tool and pin ejecting said stock completely into said die cavity.

bore of said quill, a stock gauge arranged to engage said pin to limit the length of stock fed into said bore, and a heading tool arranged to engage said pin to move said length of stock out of said quill and into said die and means in said die to hold said length of stock against axial motion, said pin in response to pressure of said heading tool deforming said length of stock in said die until substantially the entire length of stock is in the die.

3. In a header having a stock feeding station and a die, a shearing quill movable between said stock feeding station and said die, a pin slidably mounted in said shearing quill and a stock gauge spaced from said shearing quill a distance less than the length of said pin, said pin being arranged to engage said stock gauge and the end of the stock to limit the length of stock which may be fed into said quill and a heading tool arranged to engage said pin to move a length of stock out of said quill and into said die, said heading tool and pin ejecting said stock completely into said die.

4. In a header having a stock feeding station and a die, a movable shear member having an aperture adapted to be aligned alternately with said stock feeding station and said die, a plunger slidably mounted in the aperture in said shear member, a stock gauge aligned with said stock feeding station and arranged to abut said plunger when stock is fed into said aperture, said stock gauge being spaced from said shear member a distance less than the length of said plunger, means to engage said plunger when said aperture is aligned with said die to move a sheared off length of stock out of said aperture and into said die and spring means urging said plunger into a position in which said plunger clears both said die and said stock gauge.

5. In a header having a stock feeding station and a die, a movable shear arm having an aperture adapted to be aligned alternately with said stock feeding station and said die, a plunger slidably mounted in the aperture in said shear arm, a stock gauge aligned with said stock feeding station and arranged to abut said plunger when stock is fed into said aperture, said stock gauge being spaced from said shear arm a distance less than the length of said plunger, means to engage said plunger when said aperture is aligned with said die to move a sheared off length of stock out of said aperture and into said die and a coiled spring surrounding said plunger and urging the same into a position in which said plunger clears both said die and said stock gauge.

6. A header including a frame carrying a stock feeding station and a die, a header slide reciprocably mounted in said frame and carrying a punch movable toward and away from said die, a movable shear arm adapted to be aligned alternately with said stock feeding station and said die, a plunger slidably mounted in the aperture in said shear arm, a stock gauge aligned with said stock feeding station adapted to abut said plunger to limit the length of stock fed into said aperture, said punch being arranged to engage said plunger when said aperture is aligned with said die and push the opposite end of said plunger and a blank contained in said aperture into said die and means acting when said punch recedes from said die to move said plunger out of said die and project said plunger from said shear arm a distance less than the spacing of said stock gauge from said shear arm.

7. In a machine of the class described, adapted

for feeding wire or rod stock, a die spaced from the line of feed of said stock and having a diameter substantially greater than the diameter of said stock, shear means including a shear bush adapted to be aligned alternately with said die and the line of feed of said stock, a plunger slidably carried in said shear bush, said shear bush being arranged to cut off a piece of stock longer than the depth of said die and carry the same and said plunger into axial alignment with said die, and means arranged to exert pressure on said plunger to slide the piece of stock through said bush into contact with the bottom of said die, and to continue such pressure while the piece of stock is supported by said bush and the bottom of said die to upset the entire length of the piece of stock.

8. In a machine of the class described, adapted for feeding wire or rod stock, a die spaced from the line of feed of said stock and having a diameter substantially greater than the diameter of said stock, and a dome shaped bottom, shear means including a shear bush adapted to be aligned alternately with said die and the line of feed of said stock, a plunger slidably carried in said shear bush, said shear bush being arranged to cut off a piece of stock longer than the depth of said die and carry the same and said plunger into axial alignment with said die, and means arranged to exert pressure on said plunger to slide the piece of stock through said bush into contact with the dome shaped bottom of said die, and to continue such pressure while the piece of stock is supported by said bush and the bottom of said die to upset the entire length of the piece of stock.

9. A cold header including a frame having a passageway for feeding elongated stock and carrying a solid die, a reciprocating header slide, and means for cutting off pieces of stock of predetermined length and carrying the same into alignment with said die, characterized by said die having a substantially greater diameter than the diameter of the stock and having a depth less than the length of the cut off pieces of stock, said means for cutting off pieces of stock carrying a slideable plunger engaging an end of the cut off pieces, and said header slide being arranged to engage said plunger to force the cut off pieces of stock from said shear means into contact with the bottom of said die and to upset said cut off pieces of stock into said die and simultaneously push the same completely out of said shear means.

10. A header comprising a frame having a passageway for feeding elongated stock and carrying a solid die, a header slide reciprocably mounted on said frame and having a punch movable intermittently into alignment with said die, said stock feeding passageway having a diameter substantially less than the diameter of said die, shearing means including a shear bush arranged to be aligned alternately with said die and with the line of feed of said stock, said shear bush being arranged to cut off a piece of stock longer than the depth of said die and to carry the same into axial alignment with said die, and said punch being arranged to slide the piece of stock from said shear bush and upset the entire length thereof into said die, the outer end of said stock remaining in engagement with and aligned in said die by said shear bush during a substantial portion of said upsetting operation.

11. A header comprising a frame having a passageway for feeding elongated stock and carry-

ing a solid die, a header slide reciprocably mounted on said frame and having a punch movable intermittently into alignment with said die, said stock feeding passageway having a diameter substantially less than the diameter of said die, 5 shearing means including a shear bush arranged to be aligned alternately with said die and with the line of feed of said stock, a plunger slidably carried in said shear bush, said shear bush being arranged to cut off a piece of stock longer than 10 the depth of said die and carrying the same and said plunger into axial alignment with said die, and said punch being arranged to engage said plunger to slide the piece of stock from said shear bush and upset the entire length thereof into 15 said die.

12. A shearing mechanism comprising a frame having a stock feeding aperture therein, said frame having a flat surface through which said aperture passes, a die in said frame, a shear arm carrying a shear bush slidable along said surface between said aperture and said die, said bush having an aperture therein, opposing edges of the stock feeding aperture and the bush aperture at said surface serving as shearing edges, the surface of said bush at said frame surface on the opposite side of the bush aperture from the bush shearing edge being recessed to facilitate retraction of the shear arm after completion of a cutting operation, a plunger slidably carried in said shear bush, a stock gauge spaced from said frame surface serving as a stop for said plunger to gauge lengths of stock to be cut off, a reciprocably mounted header slide having a punch intermittently movable toward said bush aperture to engage said plunger and slide the cut off piece of stock from said shear bush and into said die, and means in said die to axially restrain said piece of stock, said plunger in response to pressure of said punch deforming said stock in said die until the outer end of the stock clears said bush recess.

13. In a machine of the class described, a station for receiving wire or rod stock fed thereto, a die spaced from the line of feed of stock and having a diameter substantially greater than the diameter of said stock, shear means including a shear bush adapted to be aligned alternately with said die and with the line of feed for said stock, said shear bush being arranged to cut off a piece 50 of stock at said station longer than the depth of said die and carry the same into axial alignment with said die, and tool means arranged to exert pressure on the piece of stock to slide the same through said bush into contact with the bottom of said die with the outer end of said stock protruding past the die face and extending into said shear bush, said shear bush acting to center the stock in the die with the side walls of the stock spaced from the die, said tool means continuing to exert pressure on the stock while the piece of stock is supported by said bush and

the bottom of said die to upset the entire length of the piece of stock.

14. In a machine of the class described, a station for receiving wire or rod stock fed thereto, a die spaced from the line of feed of stock and having a diameter substantially greater than the diameter of said stock and a dome-shaped bottom, shear means including a shear bush adapted to be aligned alternately with said die and with the line of feed for said stock, said shear bush being arranged to cut off a piece of stock at said station longer than the depth of said die and carry the same into axial alignment with said die, and tool means arranged to exert pressure on the piece of stock to slide the same through said bush into contact with the bottom of said die with the outer end of said stock protruding past the die face and extending into said shear bush, said shear bush and dome-shaped die bottom acting to center the stock in the die with the side walls of the stock spaced from the die, said tool means continuing to exert pressure on the stock while the piece of stock is supported by said bush and the bottom of said die to upset the entire length of the piece of stock.

15. In a machine of the class described, a station having a passageway for receiving wire or rod stock fed thereto, a solid die spaced from the line of feed of stock and having a diameter substantially greater than the diameter of said stock, means for cutting off lengths of stock and carrying them into axial alignment with said die, said stock cutting means being arranged to cut off pieces of stock longer than the depth of said die and carry the same into axial alignment with said die, and tool means arranged to exert pressure on the piece of stock to slide the same through said stock cutting means into contact with the bottom of said die with the other end of said stock protruding past the die face and extending into said stock cutting means, said stock cutting means acting to center the stock in the die with the side walls of the stock spaced from the die, said tool means continuing to exert pressure on the stock while the piece of stock is supported by said stock cutting means to upset the length of stock into said die and simultaneously push the stock through said stock cutting means.
